(57) **CLAIM**

The ornamental design for a hanging lamp support, as shown and described.

DESCRIPTION

FIG. 1 is a perspective view of the hanging lamp support according to the present invention;

FIG. 2 is a left side elevation view thereof;

FIG. 3 is a right side elevation thereof;

FIG. 4 is a front elevation view thereof;

FIG. 5 is a rear elevation view thereof;

FIG. 6 is a top plan view thereof; and,

FIG. 7 is a bottom perspective view of the hanging lamp support thereof.

The broken lines shown are for illustrative purposes only and form no part of the claimed design.
